UNITED STATES PATENT OFFICE.

CHARLES HERRMANN, OF NEW YORK, N. Y.

TELEGRAPH CALL-BOX.

SPECIFICATION forming part of Letters Patent No. 308,897, dated December 9, 1884.

Application filed February 23, 1884. (No model.)

To all whom it may concern:

Be it known that I, CHARLES HERRMANN, residing in the city, county, and State of New York, have invented certain new and useful Improvements in Telegraph Call-Boxes, of which the following is a description in such full, clear, concise, and exact terms as to enable any one skilled in the art to which my invention belongs, or to which it most nearly appertains, to make and use the same, reference being had to the accompanying drawings, making part of this specification, and to the letters and figures of reference marked thereon.

My invention more particularly relates to that form of call-box which is capable of transmitting by arbitrary signals two or more calls to be received at a distant station or stations. Boxes of this kind which have been heretofore made have been very complicated and liable to get out of order, and my present invention has in view the simplifying of the mechanism and increasing the accuracy, convenience, durability, and cheapness of such multiple call-boxes.

Figure 1 is a side view, and Fig. 2 a front view, of my improved call-box.

In these figures, 37 is a metallic box or case, which is attached to any convenient support by means of blocks of insulating material 38, 39, and 42. Within this case 37 is a system of gear-wheels and pinions pivoted in the frame 31. The spindle 47 carries the actuating-handle 19, which is fashioned at its end into a pointer, 20, also the wheels 18 and 21, and also the gear-wheel 49 and its cog-pinion 46. Fitting loosely upon this same spindle 47 is the gear-wheel 27, carrying the pawl 45, which meshes in the ratchet-teeth on the circumference of the wheel 49. The gear-wheel 27 meshes with a pinion on the arm-shaft of the toothed wheel 26, which, with the pendulum 29, forms the escapement of the gear-train. The teeth of the pinion 46 mesh into the teeth of the wheel 28, which carries a spiral actuating-spring, which is wound up when the wheel 28 is turned with a left-hand revolution.

On the insulating-block 25 is arranged the metal spring 23 and the contact 24. The spring 23 is prolonged, and carries the roller 22. This spring 23 is connected by conductor

30 with the metallic case 37, and contact 24 is connected to the binding-post 36 by means of a conductor, 32.

Upon the frame 13 is fastened, by the screw 11, which acts as a pivot, the bent lever 7, pointed at one end, and held in the position shown in the drawings by means of the spring 6, fastened to the other end thereof. The pointed end of the lever 7 rests over the periphery of the wheel 21.

Resting upon the lever 7, and near its end, as shown, is the bent lever 8, which is pivoted on the screw 12. One arm, 16, of this last-mentioned bent lever projects up and between the wheels 18 and 21, and in the plane of the revolution of the pin 17, carried by and projecting laterally from the wheel 21. The central part of this lever 8 is cam-shaped, and has upon its circumference a notch which engages the pin 14, carried by the lever 7.

Bearing upon the under side of the lever 7, and arranged to slide longitudinally in its bearings, is the push-pin 1, projecting outside of the case 37, and surrounded by the coiled spring 2.

Riveted to the top of the pin 1 is the flat contact-spring 34. This spring, when in the position illustrated, rests upon the adjustable contact 5, making electrical connection therewith. The adjustable contact 5 is supported by an insulating-block, 43. The spring 34 and contact 5 are so adjusted that any slight variation in the elevation of the pin 1 will not break the electrical connection between these parts; but when the said pin is pushed up far enough to release the gear-train, as will be hereinafter explained, the electrical connection between the said spring and contact is disrupted. The contact 5 is connected by means of the conductor 33 to the binding-post 36. The binding-post 35 forms a means of electrically connecting one of the line-wires to the metallic case 37.

The box which I have illustrated in the drawings forming part of this specification is capable of transmitting eight separate signals; but it might as well be arranged to send many more.

I will now proceed to describe the operation of the box, as illustrated, containing the said eight calls, and designed to be located at sta-

tion No. 114. The transmitting wheel 18 has its periphery cut into eight consecutive teeth, then a space, then one tooth, then a space, then one tooth, then a space, then four teeth, then 5 a space to the first of the eight consecutive teeth already mentioned. An arc of the periphery of the wheel 21 is cut into eight consecutive teeth, like those upon the transmitting - wheel 18, and the remainder is plain.

10 When in their normal positions the parts are, as illustrated in the drawings, spring 34 resting on contact 5, and thus closing the line-circuit through binding-post 36, conductor 33, contact 5, spring 10, frame 37, and binding-post 35.

15 To send a call the handle 19 is turned in the direction of the arrow until the pointer 20 stands opposite the proper letter. During this operation the teeth 4 and 1 and one on the 20 wheel 18 pass under the roller 22 on the spring 23, and when the pointer reaches the position on the plate 40 bearing the letters M E S S, one of the eight aforesaid consecutive teeth has also passed under said roller. When it has 25 reached the word "Police" two teeth have passed, and so on. Now, when the first of these eight consecutive teeth on the wheel 18 have reached the roller 22, the first of the eight corresponding teeth on the wheel 21 has come 30 in contact with the pointed end of the lever 7, which snaps over them as they pass, and prevents the gear-train reversing its motion when the handle 19 is released. This handle being fastened to the pinion 47, turns the wheel 49 35 and gear-pinion 46, which communicates its motion to the wheel 28, and thereby winds up the spring 42, attached to said wheel, the pawl 45 riding over the ratchet-teeth on the wheel 49. During this operation the electrical contact 40 between the spring 34 and the screw 5 has not yet been disrupted, and the box is, therefore, still out of circuit. When the pointer is set at the desired call, the pin 1 is pushed in, thereby lifting the spring 34 and breaking 45 the contact between it and the adjustable screw 5. The current then flows from binding-post 36, by conductor 32 to contact 24, spring 23, conductor 30 to case 37 and binding-post 35; also, when the pin 1 is pushed up 50 the straight arm of the lever 7 is raised, and the bent arm of said lever depressed, disengaging the pointed end from the teeth on the wheel 21, and also lifting the pin 14 out of its seat and tilting the lever 8, so as to cause 55 the said pin to rest on the edge of the cam 15. The wheels now revolve under the action of the coiled spring 42, and as the teeth on the wheel 18 pass under the roller 22 they lift it and alternately break and make the contact 60 between the spring 23 and contact-point 24, thus transmitting a series of impulses over the line-wire to the receiving-station, where a Morse receiver is placed, said impulses indicating the number and position of the teeth 65 which pass under the roller 22, and thereby the desired call and the number of the station

from which it is sent. This motion continues until the pin 17 presses against the arm 16 of the lever 8, when the cam 15 turns sufficiently to allow the pin 14, actuated by the spring 6, 70 to return to its seat on said cam, and at the same time the contact between the spring 34 and screw 5 is re-established, cutting the box out of circuit. The wheel 26 and pendulum 29 form an escapement to retard the motion 75 of the train while the spring 42 is uncoiling, and this escapement is actuated by the loose wheel 27, which is in turn actuated by means of the pawl 45, attached thereto, which engages with the ratchet-teeth on the wheel 49 80 when the same is turned with a left-hand revolution. The coiled spring 2 tends to lift the pin 1, so that when said pin has been pushed in, and the lever-arm 7, resting on its top, raised and suspended, the said pin retains its elevated position after pressure is withdrawn 85 from the button at its lower end, thereby keeping the spring 10 and contact 5 out of electrical connection and the box in circuit until the lever-arms fall and depress the pin, 90 as I have hereinbefore explained. By means of this shunt the apparatus is never in circuit except while transmitting a signal.

95 It will be observed that the handle 19 is placed upon the main spindle carrying the transmitting-wheels and the winding-pinion, and that the actuating-spring is carried upon a separate spindle operated by a cog-wheel meshing in the teeth of the said winding-pinion. This arrangement eliminates lost motion 100 and renders the mechanism more durable and efficient and less liable to get out of order.

Having thus described my invention, I claim—

1. In an electric call-box capable of transmitting a series of arbitrary signals, a notched engaging-wheel, 21, and a pawl, 7, which operates to arrest and hold the transmitting mechanism in any one of the several positions in which it may be set, combined with a wheel 105 for transmitting said signals, having its periphery formed as described, and a push-pin, 1, projecting outside the box, which operates to release the mechanism which transmits the signal, and at the same time automatically 110 turns the line-circuit through the signaling mechanism, substantially as set forth.

2. In an electric call-box, the combination of a notched engaging-wheel, 21, carrying a laterally-projecting pin, 17, a pawl, 7, engaging with said wheel, bearing a pin, 14, cam-lever 8, and a push-pin, 1, projecting outside the case of the box, substantially as described.

3. In an electric call-box, the combination of a notched engaging-wheel, 21, carrying a laterally-projecting pin, 17, a pawl, 7, engaging with said wheel, bearing a pin, 14, a cam-lever, 8, push-pin 1, spring 2, and contacts 5 and 34, operated and combined substantially as described.

4. In an electric call-box operated by a clock-work mechanism and capable of transmitting

a series of arbitrary signals, the transmitting mechanism, and a handle for winding up such mechanism and for indicating the signal to be transmitted, both mounted upon the same 5 spindle, combined with a spiral spring for actuating such clock-work, mounted upon an independent spindle, substantially as set forth.

5. In an electric call-box, the combination of the escapement of a gear-train with a spindle, 47, carrying a ratchet-wheel, 49, a loose gear-wheel, 27, provided with a pawl, 45, notched engaging-wheel 21, pawl 7, engaging therein, combined with a push-pin, 1, projecting outside of the box, substantially as de- 10 scribed, for the purpose specified.

6. In an electric call-box, the combination of a pawl, 7, controlling the action of the signaling mechanism, with a push-pin, 1, spring 2, and contacts 34 and 5, by means of which

the line-circuit is automatically turned through 20 the signaling mechanism when the push-pin is raised to release said signaling mechanism, but not otherwise, substantially as set forth.

7. In an electric call-box capable of transmitting a series of arbitrary signals, a signaling-wheel, 18, notched engaging-wheel to arrest and hold the transmitting mechanism in any one of the several positions in which it may be set, provided with a laterally-projecting pin, 17, and a bent lever, 16 8, combined 25 with a pawl, 7, said mechanism operating to arrest the train and short-circuit the box, substantially as described.
